(57) **CLAIM**

The ornamental design for a table, as shown and described.

DESCRIPTION

FIG. 1 is a top perspective view of a table according to a first embodiment of the design;
FIG. 2 is a front elevation view thereof to which a back view is identical;
FIG. 3 is a right side elevation view to which a left view is identical;
FIG. 4 is a top view thereof;
FIG. 5 is a bottom view thereof;
FIG. 6 is a bottom perspective view thereof;
FIG. 7 is a top perspective view of a table according to a second embodiment of the design;
FIG. 8 is a front elevation view thereof to which a back view is identical;
FIG. 9 is a right side elevation view thereof to which a left side elevation view is identical;
FIG. 10 is a top view thereof;
FIG. 11 is a bottom view thereof; and,
FIG. 12 is a bottom perspective view thereof.
The portions of the article shown in broken line form no part of the claimed design.

1 Claim, 12 Drawing Sheets
